UNITED STATES PATENT OFFICE.

GEORGE B. WHEELER, OF BROOKLYN, AND JOHN SCHILL, OF NEW YORK,
N. Y., ASSIGNEES TO GEORGE B. WHEELER & CO., OF NEW YORK CITY.

DESIGN FOR A CADDY.

Specification forming part of Design No. 7,258, dated March 24, 1874; application filed February 14, 1874.
[Term of Patent 7 years]

To all whom it may concern:

Be it known that we, GEORGE B. WHEELER, of Brooklyn, Kings county, and State of New York, and JOHN SCHILL, of the city, county and State of New York, have invented a Design for Caddy, of which the following is a specification:

Figure 1 is a side view of a caddy, illustrating our design. Fig. 2 is a front view of the same, and Fig. 3 is a top view of the same.

The nature of our design is fully represented in the accompanying drawings, to which reference is made.

A is the top of the caddy, the back part of which is made flat, and the forward part is made of an ogee form. The cover a', which forms a part of the top A, is also made of ogee form. The front of the caddy is formed of three vertical concaves, B C D. The central

concave C is the larger, being about the third part of a cylinder. The side concaves B D are about one-third the size of the central concave C, as shown in Fig. 3.

The top and front of the caddy may be japanned and ornamented as may be desired, but such ornamentation forms no part of our design.

We claim as our invention—

A design for a caddy in which the top is flat in its rear part and ogee in its forward part, and the front is formed of three vertical concaves, the central one being the larger, substantially as herein shown and described.

GEORGE B. WHEELER.
JOHN SCHILL.
